AUTOMATIC BOMB RELEASING DEVICE

Alexandre Ovtchinnikoff, Issy-les-Moulineaux,
FranceApplication April 1, 1936, Serial No. 72,134
In France July 9, 1935

7 Claims. (Cl. 89—1.5)

My invention relates to means for releasing bombs suspended from aircraft and more especially to an automatically operated device for releasing the bomb at the moment when the craft 5 passes over a point on the ground so spaced from the point to be hit that, taking into consideration the speed and altitude at which the craft is travelling, the bomb, when released, will drop on the predetermined place.

10 The invention relates quite particularly to a device of the kind aforesaid which is released automatically in dependency upon the turning, about a horizontal axis, of a telescope used as a sighting device.

15 With these and other objects in view my invention will now be described with reference to the drawings affixed to this specification and forming part thereof, which illustrate, in a purely diagrammatic manner and by way of example 20 a bomb releasing device embodying my invention.

In the drawings:

Fig. 1 is a diagram serving to explain the principle according to which the new device operates.

25 Figs. 2 and 3 are a side and end elevation, respectively, of the device as a whole and

Figs. 4, 5 and 6 are sections on the line IV—IV in Fig. 3 illustrating the device in three consecutive positions.

30 Fig. 7 is the wiring diagram.

Referring to the drawings and first to Fig. 1, which is intended to explain the effects of the displacement of an aircraft travelling at a predetermined distance above ground relative to the 35 object to be hit, S represents the ground, A the automatically active switching device serving to actuate the releasing device proper and 2 is the sighting telescope fixed to the switching device and arranged to be turned together with same about a horizontal pivotal axis O. Assuming 40 the telescope to be directed onto the point N, which marks the place or object to be hit, N₁ and N₂ are the end points of two possible curves described by a bomb when dropped at the point 45 occupied, in the drawings, by the pivotal axis O, according to the speed of flight of the craft. While the craft is displaced in the direction of the arrow relative to the ground, the trajectories, which depend solely on the altitude and the speed 50 of flight, remain the same and there is a moment when the point of intersection between these trajectories and the ground, after having passed through the positions indicated at N₁, N₂ and N₃, will reach the point N aimed at. If the altitude, 55 at which the craft is flying should change, the

ground need only be shifted graphically into a position such as S' shown in the drawings. At the moment when the point of intersection between the trajectory and the ground reaches the point N, which is the moment at which the bomb 5 must be released, the sighting line T and the vertical V extending through O enclose between them a predetermined angle α at which the switching device must automatically establish the contact for the release of the bomb. In order that the automatic establishing of this contact takes place in time, the switching device is arranged to close, by means of a mercury switch M, a first circuit to cause a chronometer 3 to start running, the moment, when this circuit is 10 closed, being determined by a sighting angle β which is much larger than the angle α and in fact larger than any angles α corresponding to all possible speeds and altitudes of the craft. This chronometer 3 is adapted to produce, a predetermined, and variable, time after the passage 15 of the telescope through a given fixed angular position, a modification in the flow of the mass of mercury of a mercury switch pivoted together with said telescope and adapted to close the circuit of the bomb release device. 20

The sighting and switching device as illustrated in detail in Figs. 2 to 6, comprises a body of mercury M filling about one half of the length of the annular conduit A into which extend two 30 contacts 13 and 22 which are spaced angularly and the first of which is connected in the circuit of an electromagnet 14, the armature 15 of which governs a rock lever 16 serving to act on a pin 17, which is arranged to set the chronometer 3 35 going. The contact 22 is connected in the electric circuit of the bomb release device proper.

The chronometer 3 is also fixed to the switching device A. 6 is a ring arranged to be turned about the chronometer and held in place by the 40 leaf spring 18. 5 is a stop formed on the ring 6 and serving to cooperate with the pointer 4 of the chronometer to cause the pointer, when the stop 5 has been set to a predetermined angular position, to be read on the scale 7 (Fig. 2) to close, 45 across the spring 18 a circuit enclosing the electromagnet 19 which governs the quantity of mercury utilized to close the releasing circuit. The two electromagnets are connected in parallel in a circuit including the wire i (Fig. 3) of the cable 8 and also the wire k leading to the body of mercury. Both these wires are connected to the poles of the battery B in Fig. 7, which also 50 illustrates the contacts 13 and 22 in a position 55

outside of the annular conduit, for the sake of simplicity.

The annular conduit A is subdivided, in its left hand half, into two concentric segments 10 and 11 by an annular partition 30. The conduit 11 is comparatively narrow; the conduit 10 is larger, but is constricted at 23. The conduit 11 is in permanent open communication with the right hand part of the annular conduit A. Communication between this right hand part of conduit A and the conduit 10 is governed by the valve 12 controlled by the armature 20 of the electromagnet 19 acting on the valve rod 21. In the right hand side of the annular conduit A there is provided a spiral-shaped element 9 which serves to reduce the rate of the flow of the mercury therethrough.

The releasing circuit, which is closed by the contact 22, comprises the wire l of the cable 8, the return wire k connected to the main body of mercury, the battery B and the igniting or other actuating device (not shown) of the releasing device proper.

The operation of the device above described is governed by the telescope 2 directed towards the point or object sighted and gradually inclined in correspondence with the reduction of the distance between this point and the craft. In the position shown in Fig. 2 the telescope A is assumed to be directed onto a point beyond the angle β in Fig. 1. In this position of the telescope the chronometer is at rest and the two contacts 13 and 22 are positioned above the mercury. In the position of the telescope shown in Fig. 4 the mercury level has reached the plane a—b right above the throttled portion 23 and corresponds to the angle β enclosed between the telescope and the vertical. In this position the contact 13 just touches the mercury so as to close the circuit of the electromagnet 15 which thereupon attracts the lever 16 to set the chronometer 3 moving, the pointer 4 of which now starts on its course. In the position shown in Fig. 5 the mercury level has reached the plane c—d extending through the constricted portion 23 of the annular conduit 10 and through a point between the contacts 13 and 22. At the same time the pointer 4 has reached the stop 5, which had previously been adjusted to the position corresponding to 13 seconds calculated by the operator as corresponding to the altitude at which the craft is travelling. Exactly 13 seconds after the telescope has entered the angle β , the circuit of the electromagnet 19 is closed, and this electromagnet in its turn closes the valve 12, thereby closing up that part of the body of mercury which is enclosed in the section 10 of the annular conduit. As the telescope continues to be turned more or less rapidly according to altitude and speed of flight, the mercury, the movable mass of which has been reduced, now passes from the plane c—d to the plane e—f (Fig. 6) which passes through the contact 22, while the mercury level in the section 10 of the conduit remains in the plane g—h. The period of time required by the mobile body of mercury to reach e—f and to close the switching circuit will obviously differ from that which the entire body of mercury enclosed in the device would require.

The period of time, within which the mercury travels from the plane a—b including the contact 13 to the plane e—f including the contact 22, and which corresponds to the rotation of the telescope between the sighting lines enclosing the angles β and α and ending in N_1 and N_2 , is the sum of a variable period defined by the posi-

tion of the stop 5 of the chronometer and the period required by the mercury to travel between the constricted portion of the annular section 10 and the plane e—f, this latter period of time depending upon the speed of flight on which depends the speed of rotating the telescope, and the altitude of flight, which acts on the position of the plane c—d. By calculation considering the altitude of flight the stop 5 can be so adjusted that the sum total of the two periods of time above defined causes the bomb to be released for the correct sighting angle which corresponds to the passage of the sighting point from N_1 to N_2 .

I wish it to be understood that I do not desire to be limited to the exact details of construction shown and described for obvious modifications will occur to a person skilled in the art.

I claim:

1. A control apparatus for use on an aircraft in connection with an electrically operated bomb release device, which comprises, in combination, a frame adapted to be fixed on said aircraft, a sighting element pivotally carried by said frame about a horizontal axis, so as to permit of keeping said element continuously pointed toward a target on the ground, an electric contactor carried by said frame including an insulating conduit with at least one contact, and a conducting liquid normally apart from said contact, means, operative by said sighting element, for producing a relative movement of said liquid in said conduit toward said contact synchronous with the movement of said sighting member when the latter is pivoted downwardly so as to be kept pointed toward the target, means for modifying the conditions of flow of said liquid in said conduit an adjustable time after said sighting element has passed through a given angular position, and an electric circuit for controlling said bomb release device including in series said contact and said liquid.

2. A control apparatus for use on an aircraft in connection with an electrically operated bomb release device, which comprises, in combination, a frame adapted to be fixed on said aircraft, a sighting element pivotally carried by said frame about a horizontal axis, so as to permit of keeping said element continuously pointed toward a target on the ground, an electric contactor carried by said frame including an insulating conduit with at least one contact, and a mass of a conducting liquid in said conduit normally apart from said contact, means operative by said sighting element for pivoting said conduit so as to produce a displacement of said mass of liquid toward said contact synchronous with the movement of said sighting member when the latter is pivoted downwardly so as to be kept pointed toward the target, means for modifying the conditions of flow of said liquid in said conduit an adjustable time after said sighting element has passed through a given angular position, and an electric circuit for controlling said bomb release device including in series said contact and said mass of liquid.

3. A control apparatus for use on an aircraft in connection with an electrically operated bomb release device, which comprises, in combination, a frame adapted to be fixed on said aircraft, a sighting element pivotally carried by said frame about a horizontal axis, so as to permit of keeping said element continuously pointed toward a target on the ground, an electric contactor carried by said frame including an insulating an-

5 nular conduit rigid with said pivoting sighting
6 element coaxially therewith, a contact in said
7 conduit, and a mass of a conducting liquid in said
8 conduit, normally apart from said contact and
9 adapted to move toward said contact when said
10 sighting element is pivoted downwardly so as to be
11 kept pointed toward the target, means for modifying
12 the section of the passage for said liquid in said
13 conduit an adjustable time after
14 said sighting element has passed through a given
15 angular position, and an electric circuit for controlling
16 said bomb release device including in series
17 said contact and said liquid.

4. A control apparatus for use on an aircraft
18 in connection with an electrically operated bomb
19 release device, which comprises, in combination,
20 a frame adapted to be fixed on said aircraft, a
21 sighting element pivotally carried by said frame
22 about a horizontal axis so as to permit of keeping
23 said element continuously pointed toward a target
24 on the ground, an electric contactor carried by
25 said frame including an insulating annular con-
26 duct rigid with said pivoting sighting element co-
27 axially therewith, a contact in said conduit, and
28 a mass of a conducting liquid, normally apart
29 from said contact and arranged to move in said
30 conduit toward said contact, when said sighting
31 element is pivoted downwardly so as to be kept
32 pointed toward said target, an annular partition
33 dividing said conduit longitudinally into two
34 chambers, extending to a distance from said con-
35 tact, means for closing one of said chambers an
36 adjustable time after said sighting element has
37 passed through a given angular position, and an
38 electric circuit for controlling said bomb release
39 device including in series said contact and said
40 mass of liquid.

5. A control apparatus for use on an aircraft
41 in connection with an electrically operated bomb
42 release device, which comprises, in combination,
43 a frame adapted to be fixed on said aircraft, a
44 sighting element pivotally carried by said frame
45 about a horizontal axis, so as to permit of keeping
46 said element continuously pointed toward a tar-
47 get on the ground, an electric contactor carried
48 by said frame including an insulating annular
49 conduit rigid with said pivoting sighting element co-
50 axially therewith, a contact in said conduit
51 and a mass of a conducting liquid in said conduit
52 normally apart from said contact and adapted
53 to move toward said contact when said sighting
54 element is pivoted downwardly so as to be kept
55 pointed toward said target, liquid control means
56 for modifying the conditions of flow of said liquid
57 in said conduit, a chronometer having a pointer,
58 an adjustable contact on said chronometer adapt-
59 ed to cooperate with said pointer for a given
60 angular position thereof, means operative by the
61 mass of liquid in said conduit for starting said
62 chronometer when said sighting element passes
63 through a predetermined angular position, an
64 electric circuit for operating said liquid control
65 means, including said adjustable contact and said
66 pointer, and an electric circuit for controlling said
67 bomb release device including in series said first
68 mentioned contact and said mass of liquid.

6. A control apparatus for use on an aircraft
69 in connection with an electrically operated bomb
70 release device, which comprises, in combination,
71 a frame adapted to be fixed on said aircraft, a
72 sighting element pivotally carried by said frame
73 about a horizontal axis, so as to permit of keeping
74 said element continuously pointed toward a target
75 on the ground, an electric contactor carried by
76 said frame including an insulating annular con-
77 duct rigid with said pivoting sighting element co-
78 axially therewith, a contact in said conduit and
79 a mass of a conducting liquid, normally apart
80 from said contact and arranged to move in said
81 conduit toward said contact when said sighting
82 element is being pivoted downwardly 15 so as to be
83 kept pointed toward the target, an annular partition
84 dividing said conduit longitudinally into two
85 chambers, extending to a distance from said
86 contact, means for closing one of said chambers
87 a chronometer having a pointer, an adjustable
88 contact on said chronometer adapted to cooperate
89 with said pointer for a given angular position
90 thereof, means operative by the mass of liquid in
91 said conduit for starting said chronometer when
92 said sighting element passes through a predeter-
93 mined angular position, an electric circuit for
94 operating said closing means, including said
95 adjustable contact and said pointer, and an
96 electric circuit for controlling said bomb release
97 device including in series said first 20 contact
98 and said mass of liquid.

7. A control apparatus for use on an aircraft
99 in connection with an electrically operated bomb
100 release device, which comprises, in combination,
101 a frame adapted to be fixed on said aircraft, a
102 sighting element pivotally carried by said frame
103 about a horizontal axis, so as to permit of keeping
104 said element continuously pointed toward a target
105 on the ground, an electric contactor carried by
106 said frame including an insulating annular con-
107 duct rigid with said pivoting sighting element co-
108 axially therewith, two contacts in said conduit and
109 a mass of a conducting liquid, normally apart
110 from said contacts and arranged to move in said
111 conduit toward said contacts, when said sighting
112 element is being pivoted downwardly so as to be
113 kept pointed toward said target, an annular partition
114 dividing said conduit longitudinally into two
115 chambers, extending to a distance from said
116 contact, a valve for closing the end of said cham-
117 ber that is nearer said contacts, a chronometer
118 having a pointer, an adjustable conducting abut-
119 ment on said chronometer adapted to cooperate
120 with said pointer for a given angular position
121 thereof, electric means including a circuit con-
122 taining in series said mass of liquid and the first
123 of said two contacts, for starting said chronometer
124 when said mass of liquid reaches said first con-
125 tact, which corresponds to said sighting element
126 passing through a predetermined fixed angular
127 position, an electric circuit for operating said valve,
128 including said adjustable abutment and said
129 pointer, and an electric circuit for controlling
130 said bomb release device including in series the
131 second of said contacts and said mass of liquid. 25
